CHARLES PARRY VAUCLAIN, OF DREXEL HILL, AND FRANK E. MERKLINGER, OF PHILADELPHIA, PENNSYLVANIA

PROCESS OF MAKING AXLE BOXES

Application filed August 5, 1929. Serial No. 383,531.

Our invention relates to improvements in the process of making the axle boxes disclosed in the application filed by us on the 2nd day of April, 1929, under Serial No. 5 351,959.

The object of the present invention is to make the body portion from a wrought metal tube, the tube being shaped, after which the pedestal guide rings are mounted on the 10 body portion.

In the accompanying drawings:

Fig. 1 is a front view of an axle box made in accordance with our invention;

Fig. 2 is a plan view;

Fig. 3 is a perspective view of the axle box with the parts assembled, with the exception of the outer ring;

Fig. 4 is a detached perspective view of the outer ring which is welded to the body 20 portion;

Fig. 5 is a vertical sectional view of the axle box;

Fig. 6 is a detached perspective view of the wrought metal tube from which the body 25 portion is made; and

Fig. 7 is a detached perspective view of the body portion made from the tube shown in Fig. 6.

The axle box illustrated in the drawings 30 is arranged to receive a roller-bearing of a standard type, but it will be understood that the box can be of any design desired without departing from the scope of the invention.

1 is the body portion of the axle box, and 35 2—2a are the two ring sections, shaped at each side as shown in Figs. 2 and 3 to form guides 3—3 which fit the pedestals of the frame in which the box is mounted.

The body portion 1 of the box is made from 40 a wrought metal tube 1a, Fig. 6. This tube is heated to a proper degree and a rear flange 4 is formed on the rear end of the tube, the forward end being rounded as at 5, leaving an opening 6 therein at the end of the body 45 portion less in diameter than the body por-

tion. This opening is clearly shown in Fig. 5.

After the body portion has been made from the tube 1a, the two rings 2—2a are forced onto the body portion, and the inner ring 2a is spaced from the flange 4 of the body portion by spacing blocks 7 (Fig. 3), and the two rings 2—2a are spaced apart by a block 8 which forms an equalizer seat. This seat has a rib 9 which extends into an equalizing beam, the beam of any suitable type. 50

Welded to the front of the body portion 1 is a ring 10 having an opening 11 of the same size as the opening 6 in the body portion. This ring is welded to the body portion and forms the support for the lid of the 60 box.

We claim:

1. The process herein described of making axle boxes, said process consisting in cutting a tube to the proper length; forming a flange 65 on one end of the tube and rounding the opposite end of the tube to form the front end of the box; mounting on the body portion two ring sections spaced apart, the ring sections having pedestal guides formed integral therewith; and welding the parts together. 70

2. The process herein described of making axle boxes, said process consisting in cutting a tube to the proper length; forming a flange on one end of the tube and rounding the opposite end of the tube to form the front end of the box; mounting on the body portion two ring sections spaced apart, the ring sections having pedestal guides formed integral therewith; securing a ring to the front of the box 80 and locating an equalizer seat between the two rings; and welding the parts together. 75

3. The process herein described of making axle boxes, said process consisting first of heating a wrought metal tube and shaping the 85 ends of the tube to form the front and rear ends of the box; and securing to said tubular body portion thus formed, two pedestal guides, said guides being spaced apart and secured to the body portion by welding. 90

4. The process herein described of making axle boxes, said process consisting of cutting a wrought metal tube, which is circular in cross section, to a given length; heating 5 the tube and shaping the ends of the tube to form the front and rear ends of the box; applying to the body of the box thus formed, ring sections having pedestal guides, the ring sections being spaced apart; and securing the 10 said ring sections to the body of the box by welding.
